Attorney

UNITED STATES PATENT OFFICE.

ALONZO C. CAMBRIDGE, OF CHARLESTON, SOUTH CAROLINA.

PARACHUTE ATTACHMENT FOR FLYING-MACHINES.

1,267,847.

Specification of Letters Patent. Patented May 28, 1918.

Application filed May 24, 1917. Serial No. 170,701.

To all whom it may concern:

Be it known that I, ALONZO C. CAMBRIDGE, a citizen of the United States, and resident of Charleston, in the county of Charleston 5 and State of South Carolina, have invented certain new and useful Improvements in Parachute Attachments for Flying-Machines, of which the following is a specification.

10 This invention relates to new and useful improvements in safety attachments for flying machines, and the device is more particularly adapted for use on aeroplanes, the same including a parachute attachment that 15 is normally closed, but which will be opened by the operator, should the machine lose its stability for any reason, and hence permit a safe descent.

Another object of the invention is to provide a device of this character which is 20 adapted to be applied to various types of flying machines, and which includes a pair of parachutes, that are normally held in operative or closed position, and which will 25 be opened instantaneously and simultaneously upon the operator pulling a single operating cord hence permitting a safe and slow descent of a disabled machine.

A still further object of the invention is 30 to provide a device of this character which is easily and simply constructed, inexpensive to manufacture, and one which will be very efficient in operation.

With these and numerous other objects 35 in view my invention consists of the novel features of construction, combination and arrangement of parts which will be herein referred to and more particularly pointed out in the specification and claims.

40 In the accompanying drawings:

Figure 1 is a side elevation of my attachment.

Fig. 2 is a top plan view of one of the 45 parachutes; and

Fig. 3 is a detail vertical section through one of the supporting standards of the 50 parachute attachment.

In describing my invention I shall refer 55 to the drawings in which similar reference characters designate corresponding parts throughout the several views. I have shown this attachment comprising a pair of parachutes, but it is obvious that if desired only one of the same may be used, but it has been, 60 found that the device is safer and operates better if a pair of parachutes are employed.

These parachutes are substantially alike in construction, and for the sake of brevity I will only specifically describe one of the same.

The parachutes are designated by the numerals 1 and 2, and they are formed of a single supporting standard 3 which is tubular, and which has formed on its lower end a base 4, provided with strengthening ribs 5, said base being adapted to be secured to 60 the aeroplane. The base is provided with an opening therethrough, and disposed adjacent to the same is a pulley 6 for a purpose to be hereinafter more fully described. A plurality of pulleys 7 are mounted adjacent 65 to the open upper end of said supporting standards, and hingedly connected with the said standard adjacent to the end are a plurality of ribs 8, which extend outwardly therefrom, and are connected with a sliding 70 collar 9 mounted on the outer surface of the standards by connecting members 10. This is the conventional type of umbrella like 75 parachute, and the same is provided with a cover 11 of any desired material which is 80 found most applicable.

Secured to the outer edges of the parachutes are a plurality of cables 12, which extend upwardly over the cover, and over the pulleys 7, down into the standards 3, 85 where their free ends are connected by a terminal ring 13. The terminal ring 13 has secured thereto an operating cable 14, which extends downwardly through the standard 90 out the open lower end thereof through the base 4, and over the pulley 6. The operating cable 14 extends between the parachutes 1 and 2, a single cable being employed, and said cable having its opposite ends connected with the terminal ring within the standards 95 3, so that the parachutes will open simultaneously. The cable 14 is provided with operating means 15 between its ends, that are positioned within easy reach of the operator of the machine, so that the cable may be 100 grasped to open the parachute when it is found necessary.

The parachutes are normally held in closed position by means of a spring 16 that surrounds the same, said spring being secured 105 thereto through loops 17, and normally holding the parachutes in closed position. The spring 16 is carried on the outer surface of the parachute, and is expansible, so that when the parachutes are opened, the spring 110 will slide through the loop members and will be held in position thereon.

In operation the parachutes are secured on the flying machine, the same being specially applicable to aeroplanes, in any desired manner, it only being necessary that the bases 4 be secured thereto, so that the operating cable will be disposed in easy reach of the operator of the machine. The parachutes are normally held in closed position by the spring 16, and when it is desired to open the same should the flying machine lose its stability and fall toward the earth, the operator grasps the operating cable 14 by the means 15, and pulls down on the same, whereupon owing to the fact that this cable is connected to the cables 12 through the terminal ring 13, said ring will be drawn downwardly through the standards 3, and as the cables 12 are connected with the outer edges of the parachute cover, said cover will be raised, the collar 9 sliding up on the standards 3. When in raised position, it is obvious that the same will be held there, and hence the descent of the crippled machine to the earth will be accomplished in perfect safety. The opening of the parachutes will not throw the spring therefrom as the same is slidably through the loop members 17 that hold it in position, and hence the spring will expand, and when the atmospheric pressure is removed from the under surface of said parachute, the spring will tend to once more close the parachute, and hold it in normally closed position.

This parachute attachment affords a simple and efficient means easily applied to various types of flying machines, that enables the same to be operated with perfect safety. The attachment may be instantaneously operated, when the machine is disabled, and said attachment will not be in any way hurt by the operation thereof, it returning to normal closed position after the machine has been landed.

From the above description, taken in con-

nection with the accompanying drawings, it is thought that a clear and comprehensive understanding of the construction, operation, and advantages of my invention may be had, and while I have shown and described the device as embodying a specific structure, I desire to have it understood, that such changes may be made in said structure as do not depart from the spirit and scope of the invention as claimed.

Having fully described my invention what I claim as new, and desire to secure by Letters Patent is:

1. The combination with a flying machine, of a pair of spaced upright parachutes carried thereby, means to normally hold said parachutes closed, cables connected with the outer edges of said parachutes, and a single operating cable connecting the ends of said first mentioned cables whereby the parachutes may be opened simultaneously.

2. A device of the class described including a tubular supporting standard adapted to be secured to a flying machine, a parachute carried by said standard, means extending through the standard for raising the parachute, and a spring surrounding said parachute to normally hold the same closed.

3. A device of the class described including a tubular supporting standard adapted to be secured to a flying machine, an umbrella like parachute carried by said standard, cables connected with the outer edges of the said parachute and extending into said standard, a terminal ring connecting the ends of said cables, an operating cable on said ring extending through said standard, and an expansible spring surrounding said parachute and secured thereto to normally hold the same closed.

In testimony whereof, I affix my signature hereto.

ALONZO C. CAMBRIDGE.
